UNITED STATES PATENT OFFICE

WILLIAM J. ELLIS, OF STEELE, ALABAMA

DOOR OPERATING MECHANISM

Application filed October 15, 1930. Serial No. 428,971.

This invention relates to door operating mechanisms and has for an object the provision of means whereby the weight of a vehicle is utilized for releasing a pair of doors when closed and automatically opening the same and holding them in open position so that the vehicle can pass within a garage and thereafter the doors will automatically close, the vehicle when within the garage, by its weight, will prevent intrusion from without as the mechanism outside of the garage will be rendered inoperative.

Another object of the invention is the provision of means for manually unlocking and opening the doors.

Another object of the invention is the provision of means of the above character which are simple in construction, reliable and efficient in use, and may be readily installed.

With the above and other objects in view, the invention further includes the following novel features and details of construction, to be hereinafter more fully described, illustrated in the accompanying drawings and pointed out in the appended claims.

In the drawings:—

Figure 1 is a horizontal sectional view taken through a portion of a garage or building with the invention applied.

Figure 2 is a section on the line 2—2 of Figure 1.

Figure 3 is a view similar to Figure 2, but with the doors in open position.

Figure 4 is an enlarged fragmentary vertical sectional view illustrating the door locking mechanism, the latter being in locked position.

Figure 5 is a similar view with the locking bolt retracted.

Figure 5A is a fragmentary vertical sectional view illustrating manually operated means to release the doors.

Figure 5B is a fragmentary elevation of the same.

Figures 6 and 7 are fragmentary sectional views taken respectively on the lines 6—6 and 7—7 of Figure 4, the dotted lines in Figure 7 illustrating the retracted position of the locking bolt.

Figure 8 is a sectional view on the line 8—8 of Figure 2.

Figure 9 is a similar view with the bolt operating platform depressed.

Figure 10 is a section on the line 10—10 of Figure 3.

Referring to the drawings in detail wherein like characters of reference denote corresponding parts, the reference characters 11 and 12 indicate a pair of doors which are hingedly mounted for horizontal swinging movement as shown at 13. One edge of the door 11 is provided with a strip 14 which overlaps the adjacent edge of the door 12 so that when the doors are closed, the door 11 will control opening movement of the door 12. The doors are yieldingly held in closed position by means of a spring 15.

The doors 11 and 12 may represent the doors of a garage, a portion of the walls of which are indicated at 16, but obviously, the invention may be applied to doors of various types.

The doors are held in closed position by means of a spring tensioned locking bolt 17 which is mounted for vertical sliding movement in a housing 18 and this bolt is adapted to engage a keeper 19 which is pivotally mounted as shown at 20 upon the door 11. The bolt 17 operates within a recess 21 provided at the entrance of the garage and the casing 18 is relatively stationary.

Extending into this recess 21 is one end of a rock shaft 22, this end of the shaft being mounted for rocking movement in a bearing 23. An arm 24 is rigid with this end of the shaft 22 and this arm has a pivotal sliding connection 25 with the bolt 17, so that vertical swinging movement of the arm 24 will impart a vertical sliding movement to the bolt 17. The other end of the shaft 22 extends away from the doors and its remote end is mounted for rocking movement in a bearing 26 which is carried by a depressible bar 27. This bar is pivotally mounted at one end as shown at 28 and extends transversely beneath one end of a depressible platform 29. This platform is inclined and its lower end is hingedly mounted as shown at 30 while its upper end is positioned above the bar 27 and

is normally elevated therefrom by a coiled spring 29' mounted between the said bar and said platform. The shaft 22 is provided with a crank arm 31 whose end extends beneath the platform 29, so that when this platform is depressed, the shaft 22 will be rocked. Rocking movement will draw the bolt 17 downward so as to disengage the same from the keeper 19, whereupon the door 11 will be released and both doors may be opened. The keeper 19 is provided with a beveled extremity 33 so that when the door 11 moves inward, the keeper will ride upon the inclined upper end of the bolt so as to engage said bolt. 15 The bar 27 is yieldingly held against downward movement by means of a spring 34, and the free end of this bar engages the upper face of an arm 35, which is pivotally mounted as shown at 36.

20 Secured to the free end of the arm 35 is one end of a flexible member or cable 37, which is trained over a guide pulley 38. The other end of this flexible member is secured to the inner end of an arm 38' which is 25 mounted for pivotal movement as shown at 39. Pivotally secured to the arm 38' as shown at 40 is one end of a link 41 and the opposite end of this link is pivotally secured to the door 11 as shown at 42.

30 Rigid with the door 12 is an inwardly and laterally inclined arm 43 which is positioned adjacent the top of the door, and the outer end of this arm has pivotally connected thereto one end of a rod 43'. The other end 35 of the rod is pivotally secured to the door 11 as shown at 44.

The platform 29 forms one section of an approach to the garage and is designed to receive the wheels upon one side of the vehicle. A platform 45 forms another section of the approach and extends from the platform 29 to the door 11. One end of the platform 29 rests upon a relatively short bar 46 which is hingedly secured as shown at 47 to the free 45 end of the bar 27, while the adjacent end of the platform 45 rests upon a beam 48 which in turn rests directly upon the bar 27. The bar 46 will be depressed in advance of the bar 27 and this bar 46 is permitted a slight 50 downward movement before downward movement of the bar 27 occurs. An approach section 49 is arranged parallel with the platforms 29 and 45, so that a vehicle approaching the garage will engage the 55 approach.

The front wheel of the vehicle will first depress the platform 29, and initial downward movement of this platform will depress the bar 46. Previous to the bar 46 reaching 60 the bar 27, downward movement of the platform 29 will, through the crank arm 31, rock the shaft 22, whereupon the bolt 17 will be retracted as previously described, and as shown in Figure 5 of the drawings. The 65 doors 11 and 12 will thus be free to swing

outward to the dotted line position shown in Figure 2. Continued movement of the vehicle will depress the platform 45, so that the bar 27 will move downward and will depress the arm 35, whereupon, a pull will be exerted upon the cable or flexible member 37 so as to swing the arm 38' outward upon its pivot 39. This will swing the door 11 outward, and through the connections 43 and 43', the door 12 will likewise be swung outward. 75

The doors will be held in this position as long as the platform 45 is depressed, and in order to prevent sudden closing movement of the doors under the action of the spring 15, the invention provides a rock shaft 50 which is mounted for rocking movement in bearings 51. This shaft 50 has a central offset portion 52 which normally rests within a recess 53, extending transversely of the upper face of the platform 45. One end of the shaft 50 carries an angularly arranged arm 54 and whose outer extremity is provided with a hook 55. This hook is adapted to engage within the socket of a keeper 56 which is carried by the door 11 so that when the door 11 is swung outward and the offset portion 52 of the shaft 50 is subsequently depressed, the arm 52 will be swung from the position shown in Figure 2 to the position shown in Figure 3, so that the hook 55 will enter the socketed 90 member 56 and hold the doors against closing movement. 95

When the vehicle is driven into the garage, the wheels will engage a crank arm 57 which is carried at one end of a rock shaft 58, the latter being mounted for rocking movement in bearings 59. This shaft 58 also carries an arm 60 and this arm is connected by means of a link 61 with one end of the arm 24. The bolt 17 being in retracted position, the crank arm 57 of the rock shaft 58 will occupy the position shown by the dotted lines in Figure 7 of the drawings. However, when the crank arm 57 is depressed through the weight of the vehicle, the shaft 58 will be rocked so that the parts will occupy the full line position shown in Figure 7 of the drawings. 100 105 110

With the parts in this position, the door 11 is still engaged by the hook 55 and in order to release the door, the shaft 50 is provided with an angularly disposed arm 62 which is adapted to extend beneath an arm 63 which is rigid with and extends from the rock shaft 22. The depressed condition of the crank arm 57 and the rocking of the shaft 58 will hold the bolt upward so that a safety device is within the garage and controlled by the weight of the vehicle on the crank arm 57 to prevent intrusion from without by the operation of the platforms to cause the opening of the doors so that it will be impossible for a person from without the garage to gain entrance thereto through the doors so long as the vehicle maintains the 115 120 125 130

crank arm 57 depressed. When the rear wheels of a vehicle leaving the garage, reach the platform 29, this platform will be depressed. The crank arm 31 will then be 5 rocked to rock the shaft 22, whereupon the arm 63 will depress the arm 62 and rock the shaft 50, and retract or disengage the hook 55 from the socketed member 56. The doors will then close under the action of the spring 10 15, and as the bolt 17 has been projected upward by spring 29', it will be in the path of the keeper 19 and this keeper will ride over and engage the upper end of the bolt so that the doors will be locked against outward 15 movement until released by depression of the platform.

In order to manually release the doors, the keeper 19 as pivotally connected to its outer end as shown at 64, one end of a link 65 and 20 the opposite end of this link has a sliding connection 66 with one end of a rod 67. The opposite end of this rod has a pivotal connection with the arm 68 which is secured to an extension 69 of a lock 70. This lock is 25 controlled by a key 71 so that when the extension 69 is rotated, the rod 67 will operate to lift the keeper 19 from engagement with the bolt. Due to the connection 66 between the rod 67 and the link 65, the keeper 19 may 30 move pivotally upward independent of the rod 67. When the doors are manually operated and moved to open position the same can be held open in any desirable manner.

The invention is susceptible of various 25 changes in its form, proportions and minor details of construction and the right is herein reserved to make such changes as properly fall within the scope of the appended claims.

Having described the invention what is 30 claimed is:—

1. In a door operating mechanism, a pair of hingedly mounted doors, means connecting said doors for simultaneous operation,

spring means to close the doors, a slidably mounted bolt, a keeper movably secured to one of the doors to engage the bolt and hold the doors closed, a normally elevated pivotally mounted bolt operating platform, means operated by said platform and connected to the bolt to retract the latter when the platform is depressed, a normally elevated door operating platform, a normally elevated depressible bar beneath the door platform and 70 adapted to be depressed by the latter, means operated by depression of the bar to open the doors when the latch is retracted, weight operated means to hold the doors in open position, and means inside relative to the doors 80 to prevent movement of the bolt to release the doors from the outside thereof.

2. In a door operating mechanism, a pair of hingedly mounted doors, means connecting said doors for simultaneous operation, spring 85 means to close the doors, a slidably mounted bolt, a keeper movably secured to one of the doors to engage the bolt and hold the doors closed, a normally elevated pivotally mounted bolt operating platform, a rock 90 shaft, means operatively connecting one end of the rock shaft and platform to rock said shaft when the platform is depressed, weight operated means to hold the doors in open position, spring operated means to project the 95 bolt into the path of the keeper, a weight operated means remote from the first named weight operated means, an arm having a sliding pivotal connection with the bolt and having one end secured to the rock shaft, a link 100 connecting the other end of the arm with the second named weight operated means, and means carried by the rock shaft and engaging the door holding means to operate the latter 105 and release the doors.

In testimony whereof I affix my signature.

WILLIAM J. ELLIS.
